XR D11.601 EX

No. 11, 601

JAN. 13, 1880

ONE HALF S

UNITED STATES PATENT OFFICE.

FRANK H. SHEPHERD, OF BOSTON, ASSIGNOR TO JAMES W. TUFTS, OF MEDFORD, MASSACHUSETTS.

DESIGN FOR HOLDERS FOR FLOWERS, MATCHES, &c.

SPECIFICATION forming part of Design No. 11,601, dated January 13, 1880.

Application filed December 10, 1879. Term of patent 3½ years.

To all whom it may concern:

Be it known that I, FRANK H. SHEPHERD, of Boston, in the county of Suffolk and State of Massachusetts, have invented and produced 5 a new and original Design for a Holder for Flowers, Matches, &c., of which the following is a full, clear, and exact description, reference being had to the accompanying photograph, making part of this specification.

10 This invention consists in a design for a holder for flowers, matches, &c., to be used as an ornament for tables, mantel-pieces, &c.

In the photograph, A represents an inverted bell, which forms a receptacle for holding flowers, matches, &c., the bell being supported by keys B, extending up from the base C, a beautiful and unique design being thus produced.

What I claim as my invention, and desire to secure by Letters Patent, is—

The design for a holder for flowers, matches, 20 &c., consisting of the inverted bell A, supported by the keys B, rising from the base C, substantially as herein shown and described.

Witness my hand this 6th day of December, A. D. 1879.

FRANK H. SHEPHERD.

In presence of—

P. E. TESCHEMACHER,
W. J. CAMBRIDGE.
